(57) **CLAIM**

The ornamental design for a set of colorful mahjong tile, as shown and described.

DESCRIPTION

The file of this patent contains at least one drawing/photograph executed in color. Copies of this patent with color drawing(s)/photograph(s) will be provided by the Office upon request and payment of the necessary fee.

FIGS. 1-34 are front plan views showing a set of colorful mahjong tile of a first embodiment of my new design;

FIG. 35 is a perspective view of FIG. 1;

FIGS. 36-69 are front plan views showing a set of colorful mahjong tile of a second embodiment of my new design;

FIGS. 70-103 are front plan views showing a set of colorful mahjong tile of a third embodiment of my new design;

FIGS. 104-137 are front plan views showing a set of colorful mahjong tile of a fourth embodiment of my new design;

FIGS. 138-171 are front plan views showing a set of colorful mahjong tile of a fifth embodiment of my new design;

FIGS. 172-205 are front plan views showing a set of colorful mahjong tile of a sixth embodiment of my new design; and,

FIGS. 206-239 are front plan views showing a set of colorful mahjong tile of a seventh embodiment of my new design.

The unclaimed thickness of each tile of the set of colorful mahjong tile in the first through seventh embodiments is uniform; the unclaimed lengths and shapes of the left and right edges of each tile of the set of colorful mahjong tile in the first through seventh embodiments are equal; and the unclaimed lengths and shapes of the top and bottom edges of each tile of the set of colorful mahjong tile in the first through seventh embodiments are equal.

The broken lines shown in FIG. 35 illustrate environmental structure that forms no part of the claimed design.
